UNITED STATES PATENT OFFICE.

CHARLES W. DAKE, OF CHICAGO, ILLINOIS, ASSIGNOR TO THE PYLE-NATIONAL COMPANY, OF CHICAGO, ILLINOIS, A CORPORATION OF NEW JERSEY.

NOZZLE GUIDE-PASSAGE.

1,397,085.

Specification of Letters Patent. Patented Nov. 15, 1921.

Application filed April 12, 1920. Serial No. 373,171.

To all whom it may concern:

Be it known that I, CHARLES W. DAKE, a citizen of the United States, residing at Chicago, in the county of Cook and State of Illinois, have invented a certain new and useful Improvement in Nozzle Guide-Passages, of which the following is a specification.

My invention relates to improvements in nozzle and guide passages for steam turbines and the like and has for one object to provide a new and improved form of turbine and nozzle and guide passage. Another object is to provide a two ring compact turbine wheel arrangement whereby one nozzle and group of guide passages will be enabled to provide the motive fluid for the buckets of two parallel groups mounted on a single turbine wheel. Another object is to provide a removable accurately fitted nozzle block so that when the nozzle wears it may be easily replaced. Another object is to provide an arrangement whereby the steam in the motive fluid may be led through two separate bucket groups with a minimum of disturbance to its flow. Another object is to provide an arrangement whereby the steam from the nozzle may pass through one group of buckets, may then be deflected passing through another group of buckets and then be discharged, all with a minimum of interference and loss by friction and inertia and the like. Other objects will appear from time to time throughout the specification and claims.

My invention is illustrated more or less diagrammatically in the accompanying drawings, wherein:

Figure 1 is a section through the nozzle and guide assembly and through a part of the turbine wheel;

Fig. 2 is a section along the line 2—2 of Fig. 1;

Fig. 3 is a section along the line 3—3 of Fig. 1;

Fig. 4 is a section along the line 4—4 of Fig. 1;

Fig. 5 are detail views in part section of the removable nozzle;

Like parts are indicated by like characters throughout.

A is the turbine housing wall, mounted upon which is the nozzle and guide passage bracket A' held in place by any suitable means, as for instance, the nuts and bolts 55 A². This bracket is located at one side of and immediately adjacent the periphery of the turbine wheel A³. This turbine wheel has mounted on either side a series of buckets A⁴, A⁶, so that there are two bucket rings 60 arranged side by side with the wheel between them and these buckets are adapted for a radial flow of the motive fluid. The bracket A' has integral with it a steam chest B communicating with the motive fluid or 65 steam supply pipe B' at one end and with a nozzle socket B² at the other end. This nozzle socket extends clear through the steam chest and is closed at one end by a plug B³ and contains the nozzle B⁴. This 70 nozzle is slotted at B⁵ and is held detachably in position in the socket by a pin B⁶ which passes through the wall of the socket and engages a group in the nozzle. The nozzle is longitudinally slotted as at B⁷ and its discharge end where it approaches the turbine wheel is curved as at B⁸ to conform generally to the curvature of the inner edge of the buckets A⁵. The slots B⁵ and B⁷ of course 75 communicate with the steam chest and the steam is conducted by it outwardly and discharged against these buckets A⁵. Because the nozzle is merely a piece of machined metal rod it can easily be made with a high degree of accuracy and it thus is possible to 80 provide with a cast steam chest and bracket a nozzle which will make a close and accurate fit and permit a minimum of spilling of steam from between the nozzle and the buckets. Any changes in size, shape and arrangement of parts can easily be compensated for by slight changes in the nozzle 85 without interfering with any of the other more permanent parts. The nozzle can also be easily removed as it wears away and be 90 replaced without interfering with any of the permanent parts.

C is a return passage block mounted on the bracket A' so as to overhang the two groups of turbine buckets. This block is 100 removably held in position by screws C'. It has cut in the face opposed to the periphery

of the turbine wheel, a series of separate inclined circular grooves arranged in a plurality of groups separated by diaphragms C²—C². These grooves are so positioned 5 that they catch the steam as it flows from the buckets A⁵, giving it a 180 degree change in direction and discharging it against the buckets A⁴, the idea being that the steam flow is so great that as its direction is 10 changed it tends to seek the outer walls of these guide passages and thus the incoming steam does not interfere with the outgoing steam. This guide passage block being removable may also be easily changed to 15 compensate for wear or to make corrections in adjustment.

It will be evident that I have illustrated an operative device still many changes 20 might be made both in size, shape and arrangement of parts without departing materially from the spirit of my invention, and I wish therefore that my drawings be taken as in a sense diagrammatic.

The use and operation of my invention 25 are as follows:

The nozzle will normally be placed in position in the steam chest and locked by means of the pin. The closure at the back 30 end of the steam chest will be closed by the plug. The guide passage block will be bolted in position and the entire assembly will then be mounted on wall of the housing and the steam line connected up. The turbine bucket will then be brought into working 35 relation with the nozzle and guide passage block so that the nozzle as above suggested discharges against the inner periphery of one group of buckets, then when steam is turned on this steam passes out 40 from the steam chest through the nozzle and is discharged against that group of buckets. Passing through these buckets it will have its direction of flow reversed and will be discharged from them against the guide passage 45 block. The guide passages will return the steam around the edge of the wheel and discharge it in the opposed direction inwardly along a radial line against the other set of buckets after which it will pass into 50 the exhaust, the idea being that each set of buckets gets one impulse from each steam particle, the steam passing outwardly along a radial line into the first set of buckets and inwardly along a radial line through the 55 second set of buckets.

The nozzle may be removed at the will of the operator by merely driving the holding pin and thus nozzles of various sizes and shapes may be introduced at the will of the 60 operator to conform to changes in character of wheel, motive fluid, or to the providing of new nozzles when wear makes that necessary.

I claim:

65 1. A nozzle for a steam turbine comprising

ing a solid cylindrical nozzle member, a socket therefor, means for supplying a motive fluid to the socket, the nozzle being longitudinally slotted along one side, the slot communicating with the steam supply. 70

2. A nozzle for a steam turbine comprising a solid cylindrical nozzle member, a socket therefor, means for supplying a motive fluid to the socket, the nozzle being longitudinally slotted along one side, the slot communicating with the steam supply, the end of the nozzle and the part of the side thereof where the slot is located being shaped to conform to the contour of the turbine wheel. 75

3. A nozzle for a steam turbine comprising a solid cylindrical nozzle member, a socket therefor, means for supplying a motive fluid to the socket, the nozzle being longitudinally slotted along one side, the slot communicating with the steam supply, means 80 for rigidly and detachably holding the nozzle in the socket. 85

4. A nozzle for a steam turbine comprising a solid cylindrical nozzle member, a socket therefor, means for supplying a motive fluid to the socket, the nozzle being longitudinally slotted along one side, the slot communicating with the steam supply, the end of the nozzle and the part of the side thereof where the slot is located being shaped to conform 90 to the contour of the turbine wheel, means for rigidly and detachably holding the nozzle in the socket. 95

5. A nozzle for a steam turbine comprising a solid cylindrical nozzle member, a socket 100 therefor, means for supplying a motive fluid to the socket, the nozzle being longitudinally slotted along one side, the slot communicating with the steam supply, means for rigidly and detachably holding the nozzle in the 105 socket, said means comprising a holding pin driven through the wall of the socket and engaging a groove in the nozzle piece.

6. A nozzle for a steam turbine comprising a solid cylindrical nozzle member, a 110 socket therefor, means for supplying a motive fluid to the socket, the nozzle being longitudinally slotted along one side, the slot communicating with the steam supply, the end of the nozzle and the part of the side 115 thereof where the slot is located being shaped to conform to the contour of the turbine wheel, means for rigidly and detachably holding the nozzle in the socket, said means comprising a holding pin driven through the 120 wall of the socket and engaging a groove in the nozzle piece.

7. A nozzle for a steam turbine comprising a solid cylindrical nozzle member, a 125 socket therefor, means for supplying a motive fluid to the socket, the nozzle being longitudinally slotted along one side, the slot communicating with the steam supply, the nozzle being partially embedded within the socket so that the wall of the socket forms 130

a closure for the slot throughout a portion of its length.

8. A nozzle for a steam turbine comprising a solid cylindrical nozzle member, a socket therefor, means for supplying a motive fluid to the socket, the nozzle being longitudinally slotted along one side, the slot communicating with the steam supply, the end of the nozzle and the part of the side thereof where the slot is located being shaped to conform to the contour of the turbine wheel, the nozzle being partially embedded within the socket so that the wall of the socket forms a closure for the slot throughout a portion of its length.

9. A nozzle for a steam turbine comprising a solid cylindrical nozzle member, a socket therefor, means for supplying a motive fluid to the socket, the nozzle being longitudinally slotted along one side, the slot communicating with the steam supply, the slot in the nozzle being of substantially constant width but of constantly increasing depth from the socket end outwardly.

10. A nozzle for a steam turbine comprising a solid cylindrical nozzle member, a socket therefor, means for supplying a motive fluid to the socket, the nozzle being longitudinally slotted along one side, the slot communicating with the steam supply, the end of the nozzle and the part of the side thereof where the slot is located being shaped to conform to the contour of the turbine wheel, the slot in the nozzle being of substantially constant width but of constantly increasing depth from the socket end outwardly.

11. In a steam turbine a wheel having a pair of separate bucket rings upon the periphery thereof, a nozzle adapted to discharge steam radially and outwardly through the buckets of one ring, a guide passage block in opposition to the outer periphery of both bucket rings arranged to return the outwardly moving steam inwardly through the buckets of the other ring, a bracket removably mounted in the turbine housing, the guide passage block being removably mounted on the bracket.

12. In a steam turbine a wheel having a pair of separate bucket rings upon the periphery thereof, a nozzle adapted to discharge steam radially and outwardly through the buckets of one ring, a guide passage block in opposition to the outer periphery of both bucket rings arranged to return the outwardly moving steam inwardly through the buckets of the other ring, the nozzle being removably socketed in the bracket.

13. In a steam turbine a wheel having a pair of separate bucket rings upon the periphery thereof, a nozzle adapted to dis-

charge steam radially and outwardly 65 through the buckets of one ring, a guide passage block in opposition to the outer periphery of both bucket rings arranged to return the outwardly moving steam inwardly 70 through the buckets of the other ring, the nozzle being removably socketed in the bracket and the guide passage block being removably mounted on the bracket.

14. In a steam turbine a wheel having a pair of separate bucket rings upon the periphery thereof, a nozzle adapted to discharge steam radially and outwardly 75 through the buckets of one ring, a guide passage block in opposition to the outer periphery of both bucket rings arranged to return the outwardly moving steam inwardly through the buckets of the other ring, a bracket removably mounted on the turbine 80 housing, a steam chest associated therewith, the nozzle being socketed in said steam chest 85 and removably positioned therein.

15. A nozzle member for steam turbines comprising a solid cylindrical part, one end of such part having flattened socket engaging surfaces, the other end and the side adjacent such end being curved to fit the contour of the steam turbine, there being a straight sided tapered slot of depth increasing outwardly toward the passage end.

16. In a steam turbine a guide passage 95 block comprising a segmental member shaped to conform to the curvature of the bucket wheel and a plurality of guide passages located in the curved face of said block, the bracket being itself removably 100 mounted on the turbine.

17. In a steam turbine a bracket removably mounted on the turbine frame having a steam passage therein, a steam chest in the bracket associated with the passage and a 105 nozzle detachably mounted and adapted to discharge steam from the steam chest against the bucket wheel, said nozzle and associated parts being located inside of the periphery of and in substantially the same plane as 110 the bucket, the bracket projecting outwardly along one side of the bucket wheel, and a guide passage block removably mounted on the bracket overlying and in the same plane as the bucket ring, the nozzle being held in 115 the steam chest by means of a removable pin which locks it against longitudinal movement.

18. In a steam turbine a bracket removably mounted on the turbine frame having a 120 steam passage therein, a steam chest in the bracket associated with the passage and a nozzle detachably mounted and adapted to discharge steam from the steam chest against the bucket wheel, said nozzle and associated parts being located inside of the periphery of and in substantially the same flow as the 125

bucket, the bracket projecting outwardly along one side of the bucket wheel, and a guide passage block removably mounted on the bracket overlying and in the same plane as the bucket ring, the guide passage block having a plurality of open semicircular inclined guide passages in the face thereof

adapted to take the steam as it travels radially outwardly through the buckets and return it radially inwardly.

10

Signed at Chicago, county of Cook and State of Illinois, this seventh day of April, 1920.

CHARLES W. DAKE.
